DESIGN FOR A JACKET

Barbara Moye, New York, N. Y.

Application December 24, 1942, Serial No. 109,132

Term of patent 3½ years

To all whom it may concern:

Be it known that I, Barbara Moye, a citizen of the United States, residing in New York city, in the county of New York and State of New York, have invented a new, original, and ornamental Design for a Jacket, of which the following is a specification, reference being had to the accompanying drawing, forming part thereof.

Fig. 1 is the front view of a jacket showing my design, and

Fig. 2 is the rear view thereof.

I claim:

The ornamental design for a jacket, substantially as shown.

BARBARA MOYE.
